The ornamental design for a dispenser, as shown and described.

DESCRIPTION

FIG. 1 is a left side, rear, perspective view of my new design; FIG. 2 is a front elevational view thereof; FIG. 3 is a rear elevational view thereof; FIG. 4 is a left elevational side view thereof; FIG. 5 is a right elevational side view thereof; and, FIG. 6 is a top plan view thereof, the bottom plan view being identical to the top plan view.
In the drawings, the dot-dot (or shorter) broken lines show perforations in the dispenser and form a part of the claimed design. The dash-dash (or longer) broken lines are for the purpose of illustrating environment only and form no part of the claimed design.
